UNITED STATES PATENT OFFICE.

OLIVER G. GILBERTSON, OF OSAGE, IOWA.

REIN HOLDER.

1,418,147.

Specification of Letters Patent. Patented May 30, 1922.

Application filed March 15, 1921. Serial No. 452,622.

To all whom it may concern:

Be it known that I, OLIVER G. GILBERTSON, a citizen of the United States, residing at Osage, in the county of Mitchell and 5 State of Iowa, have invented certain new and useful Improvements in Rein Holders, of which the following is a specification.

The present invention has to do with means for releasably securing straps and the 10 like and relates particularly to rein holding devices.

It has been my object to provide a device having unique gripping action upon a strap or line whereby the latter may be removed 15 only at the will of the user, the gripping means being actuated by a member arranged and disposed so that it will function at all times, irrespective of dirt and other causes which so readily destroy the usefulness of similar fasteners.

A further object has been to arrange the parts so that fullest cooperation therebetween will be afforded and their assembly quickly accomplished, the parts when assembled maintaining one another in operative 20 position and against displacement.

These and such other objects as may hereinafter appear are attained by the novel construction, combination and arrangement of 25 the parts to be hereinafter specifically described and claimed.

Reference will now be had to the accompanying drawing forming a part of this specification, wherein:—

- 35 Figure 1 is a side elevation of the device;
Figure 2 is a longitudinal section thereof;
Figure 3 is a detail view of the lever member;
Figure 4 is a bottom plan view;
40 Figure 5 is a similar end view; and
Figure 6 is a top view of the body portion showing a modified means for anchoring the device.

Throughout the following detailed description and the several views of the drawing, similar parts are referred to by like reference characters.

The body of the device may assume different shapes. In the drawing, it is designated 50 by the letter A and is of flanged cylindrical form and provided with a shank 7 which terminates in a bolt 8 suitably threaded to receive a nut 8' as shown in Figure 1 or in a threaded portion as depicted in Figure 6, 55 whereby the body A may be anchored upon a wall, partition, or other suitable object.

A recess 9 extends through the shank 7 and longitudinally of the bolt 8 and in this recess is seated a spring 10 which is coiled about the reduced portion of a plunger 11 60 arranged for reciprocal movement within said recess. Outward movement of the plunger 11 in the assembled device is arrested by a lever member 12 pivotally connected to the body A by the pin 13 traversing the shank 7, the latter being slotted, as best shown in Figure 6, to engage the sides of said member 12 to maintain it in vertical alignment and reinforce it against lateral strain. Upon assembly of the device, the 70 spring 10 and the plunger 11 may be inserted into the recess 9 through an aperture A' in body A provided for this purpose, and after forcing the plunger 11 back into said recess 9, the lever member 12 is positioned 75 so that the pin 13 may be made to pass through said member and the shank 7. The lever member 12 will swing upon the pin 13 as its axis, the body A limiting its forward and backward movement, while the 80 plunger 11 will be retained in the recess 9 and from which it can not be displaced so long as the lever member 12 is in position. Said plunger 11 at all times urges the lever member 12 toward the outer cylindrical wall 85 of A or against any object intermediate said wall and the lever 12, such as a strap indicated by the dotted lines of Figure 2.

The cammed inner surface of the lever member 12 indicated by the numeral 14 admits of outward movement of the plunger 11 as an incident to movement of the lever member 12 into engagement with a rein or strap, the abutting end of said plunger having a 90 shape similar to a wedge, as shown in Figures 2 and 3, to provide a bearing surface substantially as great as the diameter of the plunger 11 itself and to prevent rotation when in engagement with said lever member. 95

Serrations or teeth, 15, are provided upon the rein engaging portion of lever member 12, said serrations preferably being inclined in the direction of a handle 16 at the free 100 end of the lever, so that increased resistance will be offered when efforts to pull the rein from the device are made. By proper shaping of this surface of the lever member 12 the greatest projection of the teeth 15 may be made to coincide with the aperture A' 110 which has a diameter slightly in excess of the width of said lever member or the teeth 15

thereon, so that a pull upon a strap held in the device will cause a portion of said strap to be forced into the aperture A' by said teeth 15, thus augmenting the effectiveness of the gripping action of the device. Additional effectiveness is obtained by the use of the curved wall in body A.

Insertion of a rein or strap in the form of the invention illustrated, is from above, 10 the lever member 12 being swung out of engagement with the outer wall of A by forcing the handle 16 down and back. Preferably the free end of the rein should extend a short distance through the device to 15 enlarge the surface thereof upon which the lever member 12 may bear. That the lever member 12 may engage the rein at substantially its middle section, projections 16' are arranged upon the handle 16 at its outer ends 20 upon the side in contact with the rein to form a track for the rein, the spacing of said projections of course being in accord with the rein or strap to be used. Biting or cutting of the rein is thus avoided and 25 twisting or turning of the rein does not tend to work it loose.

The flanges upon the upper and lower sides of the body A take up the wear and lend strength to the device while the flange 30 shown in the several figures intermediate the shank 7 and the bolt portion 8 provides an enlarged anchoring surface for the device.

Without departing from the spirit of the invention, it is apparent that alterations, 35 modifications and changes which come within the scope of the claims hereto appended may be resorted to to adapt the device to the various uses which it may be given.

Having thus described my invention, what 40 I claim is new and desire to procure by Letters-Patent of the United States, is:—

1. In a rein holder, a body member having a strap receiving portion, a strap engaging

member swingingly supported thereon, and a yielding plunger mounted at one side of 45 the swinging member and normally impinging the latter to hold it in strap engaging position.

2. In a rein holder, a body member having an annular strap-receiving portion, a strap-engaging member pivotally mounted therein, 50 said member having a handle extension provided with laterally extending guide arms at one end to coact with the strap to maintain the same in proper relation to the parts 55 for insuring engagement therewith of the strap-engaging member, and a spring pressed plunger mounted in said body member and coacting with the strap-engaging member tending to shift it about its pivot and cause 60 positive engagement with the strap.

3. A rein holder or the like comprising a body having a ring portion at one end through which to insert a rein, a latch member engaging said rein, and actuating means 65 for said latch member arranged in the other end of said body, the ring portion thereof being provided with an aperture through which said actuating means are adapted to be inserted into position.

4. A rein holder or the like comprising a body having a ring portion at one end through which to insert a rein and at its other end a shank or anchoring portion, a latch member carried by said body, and actuating means for said latch member arranged in said shank or anchoring portion of said body, the ring portion thereof being provided with an aperture through which the actuating means are inserted into the shank 80 or anchoring portion, said latch member being arranged to force a strap contained in the device into said aperture to increase resistance against displacement therefrom.

In testimony whereof I affix my signature. 85
OLIVER G. GILBERTSON.
